UNITED STATES PATENT OFFICE.

ROBERT WILLIARD PAIN, OF NEW YORK, N. Y., ASSIGNOR TO THE AEOLIAN CO., OF NEW YORK, N. Y., A CORPORATION OF CONNECTICUT.

MELODY-STOP FOR MECHANICALLY-PLAYED MUSICAL INSTRUMENTS.

SPECIFICATION forming part of Letters Patent No. 717,907, dated January 6, 1903.

Application filed May 24, 1901. Serial No. 61,712. (No model.)

To all whom it may concern:

Be it known that I, ROBERT WILLIARD PAIN, a citizen of the United States, residing in the borough of Manhattan, city, county, 5 and State of New York, have invented certain new and useful Improvements in Melody-Stops for Mechanically-Played Musical Instruments, of which the following is a specification.

10 My invention relates to mechanically-played musical instruments the operation of which is controlled by a perforated music-sheet. My invention particularly relates to the sounding of an additional set of notes in this class of 15 instruments, which additional notes are comprised in a melody set of sound-producing devices.

I will describe a mechanical musical instrument embodying my invention and then point 20 out the novel features thereof in the claims.

In the accompanying drawings, Figure 1 is a vertical sectional view of a portion of a mechanical musical instrument embodying my invention. Fig. 2 is a detail front view of a 25 portion thereof. Fig. 3 is a detail view of a portion of a perforated music-sheet employed in connection with the musical instrument.

Similar letters of reference designate corresponding parts in all of the figures.

30 Fig. 1 represents the means in a mechanical musical instrument which are employed to produce a sound or note in the instrument and a sound or note in the additional or melody set of sound-producing devices. It will 35 be understood that there may be any number of the complete devices shown in Fig. 1 to make up a mechanical instrument of any size.

A represents a tracker-board, and a a perforated music-sheet passing thereover. The 40 perforated music-sheet (see Fig. 3) is provided with the usual note-perforations of a musical piece. The perforation of the note which is to be accented is, however, cut a little in advance of the other notes in a chord for a purpose 45 to be hereinafter explained. I have indicated such a note (or there may be a plurality of notes) by the reference character a¹. Obviously the note to be accented could be any one in a chord. The lines 1 and 2 indi-

cate, respectively, the beginning and end of 50 each chord. It will be observed that the note a¹ is a little in advance of the line 1.

a² represents a pipe or conduit forming a connection between a passage or duct in the tracker-board and a passage a³ leading to an 55 exhaust-chest A¹. Provided over the passage a³ where it enters the exhaust A¹ is a diaphragm a⁴, which operates pallets a⁵ a⁶. The pallet a⁵ opens a passage a⁷ to the exhaust A¹, while the pallet a⁶ opens the same passage a⁷ 60 to the atmosphere. Normally the passage a⁷ is open to the exhaust A¹.

a⁸ represents a diaphragm for closing one end of the passage a⁷, and this diaphragm separates this passage from an exhaust A². 65 The exhaust A¹ is stronger than the exhaust A², so that the diaphragm a⁸ will normally be in the position shown in Fig. 1. When, however, the exhaust A¹ is cut off from the passage a⁷, the exhaust A² on one side and the 70 atmospheric pressure on the other side will bow the diaphragm upward.

a¹⁰ and a¹¹ represent pallets operated from the diaphragm a⁸. The pallet a¹⁰ controls the vent of the passage a¹² to the exhaust A², while 75 the pallet a¹¹ controls the vent of the passage a¹² to the atmosphere. The passage a¹² is open to a pneumatic a¹³, which through a connection a¹⁴ operates a hammer mechanism of a piano or the valves controlling the speaking of a pipe in an organ.

The operation of the device as far as has been described will be readily understood. Whenever a note-opening in the music-sheet passes over a passage in the tracker-board, 85 atmospheric air passes into the passage and moves a diaphragm a⁴. The train of operations hereinbefore described then takes place.

b represents a passage which communicates with the passage a⁷. At an end of the passage 90 b there is a pneumatic b¹, which, as shown, is normally collapsed. When a passage a⁷ is vented to the atmosphere, a passage b is also vented to the atmosphere, and atmospheric pressure causes the pneumatic b¹ to expand. 95 In doing so it moves a pallet-valve b², which opens a passage b³ to the atmosphere. At the opposite end of the passage b³ is a dia-

phragm b^4 , one side of which is exposed to an exhaust in a chamber b^5 . Each diaphragm b^4 operates pallets $b^6 b^7$, one of which, b^6 , controls a vent of a chamber or passage b^8 to the 5 exhaust-chamber b^5 , and the other of which, b^7 , controls a vent for said chamber to the atmosphere. A pneumatic b^9 is open to the chamber b^8 and is normally expanded. When the positions of the pallets $b^6 b^7$ are changed, 10 the pneumatic b^9 is opened to the exhaust and is collapsed. As it collapses a rod b^{10} , connected therewith, raises a pallet b^{11} from off a vent of a reed-cell b^{12} and allows an exhaust in chamber b^{13} to draw air past a vibrating 15 tongue. Instead of vibrating tongues in the melody set of sound-producing devices reeds may be substituted therefor, and of course these reeds, which will then comprise the melody-set, may be of any stop—as, for example, viola, oboe, &c.

C represents a rod which is suitably supported at its end, so as to be rotated on its longitudinal axis and adjacent the pallets b^{11} . Loosely mounted on this rod are a number of 25 fingers c , the ends of which normally bear against the ends of the pallets b^{11} . In this position any or all of the pallets b^{11} may be raised.

c^1 represents a number of arms which are 30 fixed to the rod C , one being provided for each pallet b^{11} . Coacting with each arm is a pin c^2 , which pins c^2 are carried by the pallets b^{11} . Whenever an arm c^1 is lifted by a pin c^2 on the raising of a pallet, the rod C is caused 35 to rotate about its longitudinal axis.

c^3 represents a number of springs, one for each finger c , one end of which spring is fixed to the rod C and the other end of which spring bears against the finger. Normally 40 the springs hold the fingers against the end of the pallets b^{11} , and preferably they are of such strength as not to force the fingers past the pallets. To provide for sufficient friction to accomplish this, the ends of pallets b^{11} 45 or the ends of fingers c , or both, may be provided with felt. When, however, the rod C is rotated on its longitudinal axis, the springs are put under increased tension and cause the fingers to move to a vertical position directly 50 over the pallets b^{11} or in such a position as to prevent the pallets being raised.

c^4 represents a bar extending past all of the fingers for limiting their movement in one direction.

55 c^5 represents an arm rigidly connected at one end to the rod C and having its other end engaged by a spring c^6 . The function of this arm c^5 and spring c^6 is to return or rotate the rod C in a reverse direction, thereby releasing 60 the tension on the springs c^3 and allowing the rod C to move the fingers c to their normal position. While the fingers c are loose on the rod C there will be sufficient friction between the two to have the fingers move 65 with the rod. If desired, the springs c^3 may

be omitted. They are preferable owing to their insuring a movement of the fingers over the pallets.

In the operation of the device by reason of the melody-note being cut in advance of the other notes of a chord it permits of the operation of the pneumatic b of its note in the melody set of sound-producing devices in advance of the pneumatics b^9 of the other notes in the melody set, for to sound the note to 75 be accented in the melody set its pallet b^{11} will have to be raised, and as it rises its pin c^2 engages an arm c^1 , thereby causing the rod to rotate and move the remaining fingers over the pallets, and thus prevent any other note 80 being sounded in the melody set.

Instead of having the fingers c act to hold down pallets to prevent sound-producing devices from speaking or sounding they may act to operate or engage upon some other devices or means which if held or otherwise engaged would prevent their sound-producing devices from speaking or sounding. Hence wherever I have used the term "pallet" I mean any part or feature of a sound-producing device necessary for its sounding or speaking. It will thus be seen that according to my invention there are sound-producing devices, as embodied in the devices of the melody set, and means for operating the same, 95 and there are a plurality of yielding fingers corresponding in number to the sound-producing devices and connected to be operated when one of the devices is sounded, whereby the remainder of said devices are prevented 100 from being operated until the fingers are restored to normal position, or, in other words, the fingers are connected to be operated to prevent the operation of the remainder of the sound-producing devices when one of the said 105 devices is sounded.

The traveling music-sheet controls, as usual, the mechanisms for operating the different sets of sound-producing devices, one of which is the melody set, and the rock shaft 110 or rod C and mechanism connected thereto have the function of a mechanical locking device, which, as shown, is connected to be actuated by the operating mechanism of the melody set and is constructed to prevent the 115 operation of more than one of the sound-producing devices of the melody set at a time. This mechanical locking device is in reality a single device constructed with a plurality of fingers, whereby the operation of more than 120 one of the sound-producing devices in the melody set at a time is prevented. The rock shaft or rod C , as shown, is connected to be actuated by the operating mechanism of the melody set, and the yielding fingers c may be 125 termed "locking-fingers" for the sound-producing devices of the melody set. It will be seen that the fingers are normally in position to allow the operation of any one of the sound-producing devices of the melody set, and 130

means are provided for rocking said shaft when any sound-producing device is operated. Since the fingers are yielding, all of the fingers except the one corresponding to the sounding device operated are moved into position to lock the remainder of the sounding devices from operation.

5 The perforated music-sheet is provided with melody-note perforations, and there are governing devices controlled by the perforations in said sheet, whereby sounding devices in both the main set and the melody set may be simultaneously sounded.

Obviously my invention may be embodied 15 in widely-varying forms and some features of my invention may be used without others.

Therefore, without limiting myself to the construction shown and described nor enumerating equivalents, I claim, and desire to 20 obtain by Letters Patent, the following:

1. A melody set of sound-producing devices, means whereby the playing of a sound-producing device in said set will prevent the other devices in said set playing, and a traveling music-sheet having melody-note perforations cut in advance of the other note-perforations of the chords containing them which control said means.

2. The combination with a mechanically-played musical instrument, of an additional or melody set of sound-producing devices, and a perforated music-sheet which controls the sounding or speaking of notes in the musical instrument, and having a note-perforation of a chord cut in advance of the other notes of the chord, which perforation controls the speaking of a note in the melody set.

3. In combination with a mechanically-played musical instrument comprising sound-producing devices, an additional or melody set of sound-producing devices each having a pallet, a perforated music-sheet having melody-note perforations, a rotatable rod carrying fingers, one for each pallet, which fingers are moved from said pallets, and means for moving each of said pallets to engage a finger and cause a rotation of the rod to move the other fingers over the pallets, said means being controlled by the melody-note perforations of the music-sheet.

4. In a mechanically-played musical instrument, the combination of a set of sound-producing devices, an additional or melody set of sound-producing devices provided with pallets, a perforated music-sheet having melody-note perforations and governing devices controlled by the perforations in said sheet, whereby sound-producing devices in both sets may be simultaneously sounded, a rod provided with fingers and controlled in its operation by the governing devices controlled by the melody-note perforations, and means connected to be operated by the lifting of a pallet of a sound-producing device in the melody set for actuating said rod and fingers.

to prevent the sounding of any other device in the melody set, substantially as set forth.

5. A melody set of sound-producing devices for mechanically-played musical instruments consisting of a number of speaking or sounding devices, means for causing each of them to speak or sound comprising a pallet, a pneumatic for moving each pallet, which pneumatic is controlled by a perforated music-sheet, a rod adjacent said pallets, fingers movable with said rod when it is rotated, a number of arms carried by said rod, a pin carried by each pallet, which, when a pallet is raised, engages an arm and causes the rod to rotate and move the fingers over the remaining pallets, and means for rotating the rod in a reverse direction to move the fingers from the pallets, substantially as described.

6. In a mechanical musical instrument, the combination of sound-producing devices and means for operating the same, and a plurality of yielding fingers corresponding in number to the sound-producing devices and connected to be operated when one of the devices is sounded, and connections whereby the remainder of said devices are prevented from being operated until the fingers are restored to normal position, substantially as set forth.

7. In a mechanical musical instrument, the combination of sound-producing devices and means for operating the same, and a plurality of yielding means for interfering with said operation and corresponding to the sound-producing devices and connected to be operated when one of said devices is sounded to prevent the operation of the remainder of said devices, substantially as set forth.

8. In a mechanical musical instrument, the combination of mechanism for operating a set of sound-producing devices and an additional or melody set of sound-producing devices and operating mechanism therefor, a traveling music-sheet for controlling said mechanisms, and a rock-shaft connected to be actuated by the operating mechanism of the melody set and provided with a plurality of locking-fingers corresponding to the sound-producing devices of the melody set for preventing the operation of more than one of said devices at a time, substantially as set forth.

9. In a mechanical musical instrument, the combination of sound-producing devices, controlling devices therefor, a rock-shaft having a plurality of yielding fingers thereon arranged adjacent the said controlling devices, said rock-shaft being connected to be rocked when one of the controlling devices is actuated to move the fingers into position to lock the remainder of the controlling devices from movement, substantially as set forth.

10. In a mechanical musical instrument, the combination of a set of sound-producing devices, means for controlling the operation of the same, a rock-shaft, a plurality of yielding fingers connected to said shaft, said fin-

gers being normally in position to allow the operation of any of the sound-producing devices, and means for rocking said shaft when any sound-producing device is operated, 5 whereby the fingers are moved into position to prevent the operation of the remainder of the sound-producing devices, substantially as set forth.

In testimony whereof I have signed my name to this specification in the presence of two subscribing witnesses.

ROBERT WILLIARD PAIN.
